UNITED STATES PATENT OFFICE.

JOHN VONS, OF CLEVELAND, OHIO.

VENDING-MACHINE.

1,351,590.

Specification of Letters Patent. Patented Aug. 31, 1920.

Application filed June 5, 1919. Serial No. 301,983.

To all whom it may concern:

Be it known that I, JOHN VONS, a citizen of the United States, resident of Cleveland, county of Cuyahoga, and State of Ohio, have invented new and useful Improvements in Vending-Machines, of which the following is a specification, the principle of the invention being herein explained and the best mode in which I have contemplated applying that principle, so as to distinguish it from other inventions.

My invention relates to vending machines and particularly to machines of this character adapted to hold a plurality of circular cans or similar containers and dispense the same one at a time as required. Particularly does the invention relate to a vending machine of this character in which apparatus economically manufactured and assembled shall with certainty discharge the contents only upon the machine being played by a perfect coin of the proper denomination.

The annexed drawings and the following description set forth in detail certain means embodying my invention, the disclosed means, however, constituting but one of the various mechanical forms in which the principle of the invention may be employed.

In said annexed drawings:

Figure 1 represents a side elevation of the apparatus, parts being shown in section, the operating lever being shown in normal position;

Fig. 1^a represents a transverse section taken in the plane indicated by the line I^a—I^a, Fig. 1;

Fig. 2 represents a view similar to that shown in Fig. 1, the operating lever being shown in the extreme forward position and a can being shown as delivered;

Fig. 3 is a vertical longitudinal section, taken in the plane indicated by the line III—III, Fig. 12;

Fig. 4 represents a vertical longitudinal section taken in the planes indicated by the line IV—IV, Fig. 12;

Fig. 5 represents a vertical longitudinal section taken in the planes indicated by the line V—V, Fig. 12, all parts in Figs. 3, 4 and 5 being shown in those positions which

they respectively occupy when the operating lever is in its normal position;

Figs. 6, 7 and 8 represent, respectively, views similar to those shown in Figs. 3, 4 and 5, except that, in said Figs. 6, 7 and 8, the parts are shown in those positions which they respectively occupy when a coin has been inserted into the machine and has dropped through and from a coin chute and into a slot in a longitudinally reciprocable member hereinafter more fully described;

Figs. 9, 10 and 11 represent, respectively, views similar to those shown in Figs. 3, 4 and 5, except that the several parts are shown in the respective positions which they occupy when the operating lever has been moved to its extreme forward position;

Figs. 12 and 13 represent, respectively, longitudinal horizontal sections taken in the planes indicated respectively by the lines XII—XII and XIII—XIII, Fig. 3;

Figs. 14 and 15 indicate vertical transverse sections taken in the respective planes indicated by the lines XIV—XIV and XV—XV, Fig. 3.

Referring to the annexed drawings, there is therein disclosed a main frame 1 constructed in any suitable manner and in which are mounted any desired number of 80 communicating inclined planes upon which, through a suitable door member 1', a plurality of containers 4 are adapted to be positioned and down which planes they are fed in the manner hereinafter fully described. For the purposes of illustration, I have shown in the accompanying drawings two of said communicating inclined planes, indicated by the ordinals 2 and 3, respectively. These planes or tracks are each 85 formed by a pair of channels 2'—2' and 3'—3', respectively, secured to the side members of the main frame 1 and upon the projecting flanges of which the containers 4 ride. The sides of the frame 1 with the channels 2'—2', 3'—3' already secured thereto are assembled with the top, bottom and end members to form the casing 1. The

operating mechanism is adapted to be supported by and, for the most part, in a casing 5 suitably mounted in the lower right-hand corner of the main frame 1, as plainly

shown in Figs. 1 and 2, the upper surface of said casing 5 also being formed to provide an inclined plane. The inclined plane 3 does not feed directly to the inclined plane 5 formed by the casing 5, but there is provided intermediately of said inclined planes 3 and 5 an auxiliary track section 6 suitably pivoted upon a pin 7 suitably mounted in the bracket 8 supported by the casing 5. Said track section 6 consists of an upper track section proper 6' and a lower arm 6'', respectively. The pivotal action of the track 6 is adapted to transfer the foremost container 4 from the inclined plane 3 to the uppermost point 9 of the inclined plane 5, all as hereinafter described in detail. The normal position of the pivoted track 6 is that plainly shown in Figs. 1 and 3 and is maintained by means of a suitable spring 10. Upon the floor 11 of the casing 5 a longitudinally reciprocable plunger 12 is positioned and provided with suitable guides 63' and 51''. The normal position of said plunger 12 is that plainly shown in Figs. 3, 4 and 5 and the same is maintained by a spring 13 fastened at its respective ends to a pin 17 extending downwardly from the forward end of the plunger 12 and to a bracket 18 secured to the floor 11 of the casing 5. Laterally extending from the plunger 12 and intermediately of the ends thereof, are two pins 19, Figs. 12 and 13, the purpose of which will be hereinafter fully explained. Secured to the side of the plunger 12 opposite that from which the pins 19 project, is a frame 14 whose design and plan is plainly shown in Fig. 13 and which is provided with a coin slot 15. This frame 14 is provided with surfaces in three horizontal planes, the lowermost of which is indicated by the ordinal 14', the intermediate of which is indicated by the ordinal 14'', and the highest of which is indicated by the ordinal 20. Secured upon the upper surface of the plunger 12 adjacently the frame 14 is a projection 16. The purposes of these several features centered about the frame 14 will be hereinafter fully described. It is designed that by means not yet described, a coin 21 shall be delivered into the slot 15, but not therethrough in the first instance, the bottom of the slot being closed by means of the floor 11 of the casing 5 in the normal position of the parts, as plainly shown in Figs. 3 and 4. It is also designed that if a bogus coin or an imperfect coin, too heavy or too light, is fed into the machine, it shall not reach the slot 15. The position of a genuine coin 21 which is now being described, is plainly illustrated in Fig. 7.

Mounted in suitable brackets in the casing 5 is the crank shaft 23, to the outer end of which a suitable crank arm 24 is secured, suitable stops 26 and 25 being provided to

limit the respective forward and rearward movements of the crank arm 24. Mounted upon the shaft 23 adjacently the crank arm 24 and secured to said crank arm by a pin 28, is a circular segment 27 formed with a coin receiving slot 29. Mounted upon said shaft 23 and adjacently the other end thereof is a member 30 provided with a cam surface 31 adapted, when the crank arm 24 is actuated, to act upon a lever 32 pivoted at its upper end in a bracket 33 secured to the under face of a plate 62 which in turn is secured to the underface of the inclined plane 5. The lower end of said pivoted arm 32 extends through the space between the pins 19 hereinbefore described as extended laterally from the reciprocable plunger 12.

Also secured to the under face of the plate 62 are members forming a coin chute 34, having an open side 34', and rear face openings 34'', plainly shown in Figs. 7 and 14. An obliquely, longitudinally disposed arm 36, provided with a front face portion 37, extended through and forwardly of the casing 5, is pivotally secured at its inner end to a downwardly extending member 38 pivotally supported by the plate 62 by a pin 38' and adapted to clear the coin slot 29 in the segment 27 and the coin slot 34', if the weight of a container 4 or containers is bearing against the face portion 37, as plainly shown in Fig. 3. If no such pressure is being exerted upon the face portion 37 of the arm 36, then the shutter 38 is closed over the coin slot 29 and the coin slots 29 and 34' do not communicate and no coin can be put into the machine. This obviates any chance of playing the machine, when no containers are therein.

Disposed adjacently the lower parts of the sides of the coin chute 34 and the bottom thereof is a pivoted coin retaining frame 39 provided with a depending lip portion 40, said frame 39 being pivotally supported upon the outer end of a resiliently held arm 41 pivotally mounted in a bracket 68 depending from the plate 62, by means of a pin 68', the exact normal position of the swinging frame 39 being determined by the strength of a spring 67 secured at one end to the arm 41 and at the other end to arm 115 68'' threaded at one end upon a pin 69 mounted in the upper end of the walls of the coin chute 34. It will be readily understood that the actuation of a nut 70 will determine the position of the threaded arm 68 upon the pin 69 and hence the strength with which the spring 67 holds the swinging frame 39. The object of this last-described construction is that when a proper coin is inserted through the recesses 29 and 34' and falls down the chute 34, it shall rest upon the bottom member of the frame 39, as shown in Figs. 3 and 4, and depress said

frame an amount sufficient to effect the proper functioning of the machine in the manner hereinafter fully described. It might be stated here that if too light a coin 5 is inserted, the frame 39 will be depressed too slight an amount, and if too heavy a coin is inserted, said frame will be depressed too great an amount, with the results hereinafter fully described. It might also be 10 stated that the three different levels hereinbefore described obtaining to the reciprocable frame 14, coöperate with the several amounts of depression imparted to the coin retaining frame 39 by too light, perfect, and 15 too heavy coins, respectively, in the manner hereinafter fully described.

Mounted upon a pin 42 suitably supported in a member 48 and retained in a normal position by means of a spring 43, is 20 a pivoted frame 44 provided with a rearwardly extending bent arm 45, said arm extending laterally through a slot 47 intersecting the bottom of the member 48, said frame 44 being adapted to be pivotally 25 swung, in a manner hereinafter fully described, against the action of the spring 43, so that said outward extending portion of the arm 45 shall be depressed and the bent portion thereof shall contact with the rear 30 wall 46 of the slot 47, and the main portion thereof shall lie in the path of the projection 16, for the purpose hereinafter fully described. Said pivoted frame 44 is disposed in the longitudinal vertical planes 35 passing through the coin slot 15, for a purpose hereinafter fully described. The bottom rear corner of the member 48 is downwardly extended and then outwardly bent to form a hook 49 adapted to slide under a 40 guide 63² formed upon a hood 63 hereinafter more fully mentioned and an upwardly extended bridge portion of which forms the guide 63' for the reciprocable plunger 12 hereinbefore fully described. A 45 downwardly extending portion 48' of the member 48 bears upon the floor 11. The forward end of the member 48 is formed to receive a pin 50 upon which is pivotally supported the lower arm 6² of the pivoted 50 track section 6 which has been hereinbefore described and is pivoted upon the pin 7. Pivoted upon a pin 51', a roller portion of which 51² forms the rear guide for the reciprocable plunger 12, is a frame 51, to the 55 outer end of which is pivoted, by means of a pin 53, a frame 52 in turn pivoted intermediately its ends to an outwardly extending arm 54 also pivoted upon the pin 7. The upper end of the arm 52 is adapted, in 60 certain positions of the mechanism, to extend up between the adjacent sections of the inclined plane 3 and the pivoted track 6, to prevent the containers 4 from rolling by gravity from said plane 3 onto the plane

normally occupied by said track 6, as 65 plainly shown in Fig. 9.

Formed in the floor 11 of the casing 5 is a coin slot 55, Fig. 13, leading to a coin box 56. Two comparatively large openings 61 and 61', respectively, disposed forwardly and rearwardly of the transverse planes passing through said coin box 56, are also formed in said floor 11 for a purpose hereinafter fully described.

Suitably pivotally supported upon a pin 59 from the bracket 60, secured to the plate 62, is a swinging frame 58 of non-magnetic material to which is secured a horse-shoe magnet 57 normally held adjacently the slots 34² of the coin chute 34. The walls 80 of said coin chute are also made of non-magnetic metal. This magnet is for the usual purpose of holding a bogus coin or slug if the same is inserted through the coin openings 29 and 34' into the chute 34. 85 At a suitable point in the operation, the swinging hanger 58 is pulled away from the coin chute 34 to release the slug by the means now to be described. One side of the swinging hanger 58 is formed with an extending arm 58' which lies in the path of movement of the pivoted arm 32 and is intersected by the latter to withdraw the swinging frame 58 from the coin chute 34, at a certain point of the movement of the 90 lever 32 to be hereinafter fully described. Secured to the forward portion of the floor 11 of the casing 5 is the bridge 63 hereinbefore mentioned, and of the general design and plan plainly shown in Fig. 13. This 100 bridge is in reality a cover or hood for certain parts of the mechanism and is provided with the lip 63² hereinbefore mentioned, the under surface of which forms a guide for the extending hook portion 49 105 of the member 48. Pivotally mounted upon the axis 23 and adjacently the far end thereof, as seen in Fig. 3, is a swinging frame 65, Figs. 5, 8 and 11, formed at the bottom with two laterally extending, outwardly turned lips 65'. This frame is for the purpose of positively insuring the return of the several mechanisms to normal positions, after the machine has been played and the crank handle is moved from right 110 to left, Fig. 2. The several positions of this swinging frame 65 are plainly shown in said Figs. 5, 8 and 11, the same in the normal position of the apparatus being held by the arm 30 and lip 65' in the position 115 shown in Fig. 5, swinging freely in the position shown in Fig. 9, and carried by the arm 32 to the position shown in Fig. 11, when the parts are in their extreme forward positions.

It will be evident that the operation of the afore-described mechanism is as follows:

Assuming that the parts are in the sev-

eral normal positions indicated in Figs. 1, 3, 4, 5, 12, 13, 14 and 15, a perfect coin is inserted through the coin slots 29 and 34' which register because they are designed to 5 register when a container or containers are bearing against the face portion 37 of the plate 36, as shown in Fig. 3, said coin being intended to deliver to a forwardly disposed accessible pocket 66, the container 4, of 10 which a full end view is shown in Fig. 3. Said coin falls to the bottom of the chute 34 and depresses a proper amount the swinging frame 39, as plainly shown in Fig. 4. The actuation of the crank arm 24 results, 15 through the medium of the cam face 31, in an immediate rearward movement of the pivoted lever 32 which, through the medium of the pins 19, results in the immediate rearward movement of the reciprocable plunger 12 against the action of the spring 13. At 20 the commencement of this movement of the plunger 12, the frame 14 is disposed forwardly of the hook portion 49, so that the coin slot 15 in said frame 14 is gradually 25 brought nearer and underneath the swinging frame 39 on the upper surface of the bottom side of which the coin is being held. Just so soon as the level 14² of the frame 14 intersects the lip 40 of the frame 39, the 30 pivoted frame 39 is carried rearwardly and, inasmuch as the upper part of the coin 21 is still retained by the side walls of the chute 34, said coin cannot be carried rearwardly by said swinging frame 39, and consequently 35 falls into the slot 15 which, at that proper moment, is disposed directly underneath the chute 34, which slot 15 has its lower end closed by the floor 11 of the casing 5, as plainly shown in Fig. 7. The continued 40 actuation of the crank handle 24 results in the continued rearward movement of the plunger 12 and consequently the member 14 carrying the coin 31. The upper part of said coin intersects the depending and forwardly 45 extending pivoted member 44 and carries same rearwardly for its limited pivotal movement, *i. e.*, until the laterally extending bent portion 45 thereof meets the rear side wall 46 of the slot 47. Then the member 48 50 including the pivoted frame 44 which can be swung no further, is carried rearwardly by the pressure of the projection 16 upon the depressed member 45, this rearward movement of the member 48 resulting because of 55 its pivotal connection with the lower arm 6² of the pivoted track section 6 in a lifting of the upper arm 6' of said track section 6 and the consequent lifting of the container 4 positioned thereon up over the forward upper 60 point 9 of the inclined track 5, whence said container 4 rolls down into the pocket 66. This continued rearward movement of the frame 14 has carried the coin 21 contained in the slot 15 to a point where said slot 15 65 registers with the slot 55 formed in the rear

portion of the floor 11 of the casing 5 and the coin drops through said slot 55 into the coin chamber 56, as plainly shown in Fig. 10. At the same time the rearward movement of the plunger 12 has resulted in the 70 rear beveled face 12' of the same co-operating with a bevel face 51² formed in the lower surface of the pivoted member 51, thus lifting said member 51 and consequently lifting the pivoted frame 52, the upper end of which 75 extends up forwardly of the subsequent can 4 and prevents the same from rolling into the open space normally occupied by the pivoted track section 6'. The release of the crank arm 24 results, through the action of 80 the spring 13, in the movement of all of the parts to their normal positions, this consequent withdrawing of the barrier formed by the upper end of the frame 52 resulting in a rolling of the next can 4 upon the pivoted 85 track section 6 which, in common with the other parts of the mechanism, has retaken its normal position.

In the event that a bogus coin 22 is inserted through the coin slots 29 and 38', the 90 same is held in the upper part of the coin chute 34 by the magnet 57. This magnet is not withdrawn by the action of the lip 58' and arm 32 until the coin slot 15 has passed beyond the vertical plane containing the 95 coin chute 34, so that said bogus coin 22 falls upon the floor 11 of the casing 5 and is swept from said casing through the opening 61 out of the machine by the frame 14 when the same is coming back to its normal position, 100 as plainly shown in Fig. 10. In the event that a coin too light is put into the machine, the same will not depress the pivoted frame 39 sufficiently to allow the lip 40 to be intersected by the surface 14² of the frame 14, 105 but the highest point or surface of said frame, which is indicated by the ordinal 20, will intersect said lip 40 to release the coin from the frame 39 and from the chute 34. This, of course, happens after the coin chute 110 15 has passed beyond the vertical plane containing the chute 34, so that the light coin falls upon the floor 11 of the casing 5 and is swept out through the opening 61 upon the return movement of the 115 frame 14. In the event that a coin too heavy is put into the machine, the same depresses the frame 39 to an extent sufficient to allow the lowermost surface 14' of the frame 14 to intersect the swinging frame 39, so 120 that the heavy coin is released from the frame 39 and the chute 34 before the coin slot 15 registers with the chute 34, the result being that the heavy coin falls upon the floor 11 rearwardly of the frame 14 and is 125 swept by the frame 14 over the narrow slot 55 and out of the machine through the opening 61', as will be readily understood.

What I claim is:

1. In a vending machine, a coin operated 130

mechanism, comprising a coin chute, a pivoted coin retaining frame disposed adjacently to the lower parts of the sides of the coin chute, an operating plunger shiftable 5 transversely across the lower end of the chute, and a frame carried by said plunger provided with a plurality of horizontally disposed levels adapted to coöperate with said retaining frame to release coins therefrom at different positions of the plunger.

2. In a vending machine, a coin operated mechanism, comprising a coin chute, a pivoted coin retaining frame resiliently disposed adjacently the lower parts of the sides 15 of the chute, an operating plunger shiftable transversely across the lower end of the chute, and a frame mounted on said plunger at one side thereof having a plurality of horizontally disposed levels adapted to coöperate with said retaining frame to properly dispose of the coins.

3. In a vending machine, the combination of a main frame, a casing mounted in said frame by which the operating parts are supported, a coin chute mounted in said casing, a pivoted coin retaining frame resiliently disposed adjacently the lower parts of the sides of the chute, a longitudinally reciprocable plunger mounted in said casing, and a 25 frame carried by said plunger provided with surfaces disposed in three horizontal planes and adapted to contact with said retaining frame to release coins therefrom at three different positions of said plunger.

35 4. In a vending machine, the combination of a main frame, a casing mounted in said frame by which the operating parts are supported, a coin chute mounted in said casing, a pivoted coin-retaining frame disposed beneath said chute and close enough to be depressed by the weight of the coin, means for adjusting the resiliency of said pivoted frame, a longitudinally reciprocable plunger mounted in said casing, and a frame carried 40 by said plunger in the path of the pivoted frame provided with surfaces disposed in three horizontal planes and adapted to contact with said pivoted frame to release coins therefrom at three different positions of said plunger.

50 5. In a vending machine, a coin operated mechanism, comprising a coin chute, a pivoted resiliently supported coin retaining frame disposed beneath said chute and close enough to be depressed by the weight of the coin, means for regulating the resiliency of said frame, an operating plunger shiftable across the lower end of the chute, and a frame carried by said chute provided with 55 a plurality of horizontal levels adapted to assort and properly distribute the genuine coins from the spurious coins by the shifting movements of said plunger.

60 6. In a vending machine, a coin operated mechanism, comprising a coin chute, a piv-

oted resiliently supported coin retaining frame disposed beneath said chute and close enough to be depressed by the weight of the coin, a lip depending from said frame, means for adjusting the resiliency of said 70 frame, an operating plunger shiftable across the lower end of the chute, a frame mounted at one side of said plunger in the path of said pivoted frame provided with three horizontally disposed levels, said levels being so 75 arranged that a coin too light will not be released from the coin-retaining frame until the highest level contacts with said pivoted frame in its forward movement, whereby the spurious coin is released and allowed 80 to fall and be swept out of the machine upon the return movement of the plunger.

7. In a vending machine, a coin-operated mechanism, comprising a coin chute, a pivoted resiliently supported coin retaining 85 frame having a depending lip disposed beneath said chute close enough to be depressed by the weight of a coin, means for regulating the resiliency of said frame, an operating plunger shiftable transversely across the 90 lower end of the chute, a frame carried by said plunger and mounted at one side thereof in the path of said pivoted retaining frame, said last-named frame having surfaces disposed in a plurality of different 95 levels, said levels being so arranged that a coin too heavy will depress the coin retaining frame into contact with the lowermost level during its rearward movement whereby the spurious coin is released and swept 100 out of the machine by the continued rearward movement.

8. In a vending machine, a coin operated mechanism, comprising a coin chute, a pivoted resiliently supported coin-retaining 105 frame provided with a depending lip and disposed beneath said chute close enough to be depressed by the weight of a coin, means for regulating the resiliency of said frame, an operating plunger shiftable transversely 110 across the lower end of the coin chute, a frame mounted on said plunger in the path of the pivoted frame and provided with a plurality of horizontally disposed levels adapted to coöperate with said coin retaining frame to release coins therefrom at different 115 positions of the plunger.

9. In a vending machine, a coin operated mechanism comprising a coin chute, a pivoted resiliently supported coin-retaining 120 frame disposed beneath said chute, an operating plunger shiftable across the lower end of the coin chute, and means carried by said plunger and adapted to contact with said pivoted frame at three different positions of 125 the plunger for releasing the coins, and whereby all coins are assorted and properly distributed.

10. In a vending machine, a coin-operated mechanism, comprising a coin chute, a 130

swinging resiliently supported frame disposed beneath said chute, means for varying the resiliency of said frame, an operating plunger shiftable across the lower end of the chute, a frame secured to said plunger provided with a coin slot, said last mentioned frame being provided with surfaces disposed in three horizontal planes and

adapted to contact with said swinging frame to release coins therefrom at three different 10 positions of the plunger, and means operated direct by a genuine coin for assuring the delivery of an object.

Signed by me, this 31st day of May, 1919.

JOHN VONS.
